ALTERNATING TO DIRECT CURRENT CONVERTER

Thomas N. Urquhart, Troy, Michael A. Koltuniak, Warren, and Robert G. Plantholt, Rochester, Mich., assignors to Controlled Power Corporation, Farmington, Mich.

Filed July 18, 1969, Ser. No. 18,274

Term of patent 14 years

Int. Cl. D13—02

U.S. Cl. D26—15

FIG. 1 is a front elevation of an alternating to direct current converter, showing our new design;

FIG. 2 is a side elevation as viewed from the right of FIG. 1;

FIG. 3 is a side elevation as viewed from the left of FIG. 1;

FIG. 4 is a rear elevation thereof;

FIG. 5 is a top plan view thereof; and

FIG. 6 is an enlarged fragmentary sectional view taken on line 6—6 of FIG. 1 to bring out the grill ornamentation of each module.

We claim:

The ornamental design for an alternating to direct current converter, substantially as shown and described.
